UNITED STATES PATENT OFFICE.

GEORGE M. EAMES, OF BRIDGEPORT, CONNECTICUT.

METHOD OF STRAIGHTENING NEEDLES, WIRE, &c.

SPECIFICATION forming part of Letters Patent No. 331,386, dated December 1, 1885.

Application filed May 7, 1885. Serial No. 164,657. (No model.)

To all whom it may concern:

Be it known that I, GEORGE M. EAMES, a citizen of the United States, residing at Bridgeport, in the county of Fairfield and State of Connecticut, have invented certain new and useful Improvements in Processes of Straightening Needles, Wires, &c.; and I do hereby declare the following to be a full, clear, and exact description of the invention, such as to will enable others skilled in the art to which it appertains to make and use the same.

My invention relates to certain new and useful improvements in the method of straightening needles, wire, tubing and the like, and has for its object to accomplish the desired result in a manner that shall be extremely accurate and entirely automatic; and with these ends in view my invention consists in revolving the object to be straightened across the path of the straightening mechanism, and in controlling the operation of the straightening mechanism by the eccentricities of the object to be straightened.

In order that those skilled in the art to which the invention appertains may fully understand my improved method and operation, I will proceed to describe the same, referring by letter to the accompanying drawings, forming a part of this specification, in which is shown one form of machine for carrying out my invention.

Figure 1 is a side elevation of my machine; Fig. 2, an end view; Fig. 3, a plan, the electric circuit being shown in diagram, and Fig. 35 4 an end elevation showing a modification of my improvement.

Similar letters denote like parts in the several figures of the drawings.

A is the bed-plate, which supports the operative parts of the machine.

B is a standard secured to the bed-plate, and having journaled therein a sleeve, C, on which is mounted the gear-wheel D.

E is a spindle, which passes through the sleeve C and is splined thereto, so that any revolution of the former will be transmitted to the latter. The inner end of the spindle is journaled within a standard, F, which is secured to the bed.

50 G is a rod supported by the standards E F, on which is pivoted the heel end of the sec-

tional nut H, confined between the collars I. This nut, when in position, engages with threads J on the spindle E, so that when the latter revolves it will have a longitudinal feeding movement, as will be presently explained. The inner end of this spindle is provided with a chuck, K, or other device for holding the object to be operated upon.

L is an anvil supported by the standard M, over which the needle or wire is fed and revolved by the action of the spindle.

N and O are standards, in which is journaled the shaft P, having mounted thereon the gear-wheel Q, which is preferably of greater diameter than the wheel D, from which it receives its motion through the idle-wheel R.

Mounted upon the shaft P, and insulated therefrom, is a yoke, S, which forms a part of the electro-magnet T; also on this shaft is loosely mounted a disk, U, of soft iron, forming the armature of the magnet and having secured to its shank an arm, V, which extends to a point over the anvil L and forms the handle of the hammer W.

X is a spring coiled around the shaft P between the yoke and armature-disk, and serves to keep the latter in its normal position out of contact with the poles of the magnet, for the purpose hereinafter explained.

Y are commutator-rings secured to and insulated from the shaft P, and Z Z' are their metallic brushes, secured to the bed-plate and in constant contact with their respective rings.

A' is a contact-lever pivoted to the insulated post B'. The normal position of the upper extremity of this lever is in a vertical plane whose distance from the axial line of the needle or wire is constant.

C' is a coiled spring, attached to the insulated post D' and lower end of the lever A', and retracts the latter against the thumb-screw E' by which the normal position of said lever is regulated.

The electric-circuit, as shown in diagram in Fig. 3, is as follows: F' is the electric source from whence the circuit proceeds in a direction of the arrows c to the positive (+) commutator-brush and its ring, from thence by the arrows d to the electro-magnet, thence by the arrows e to the remaining or negative commutator Z', by arrows f to the binding-post

D', through the spring C', to the contact-lever, and, when the latter is in contact with the needle, from thence through the spindle E to the frame of the machine, and finally from the 5 post G' to the source by arrows g.

From the foregoing description the operation of my improvement will be obviously as follows: A needle having been inserted in the chuck the spindle is revolved by means of a 10 crank or pulley, and will be fed backward, as before described. Now, if the needle revolving in front of the contact-lever be out of true, its eccentricities will come in contact with said lever on its upward movement, thereby completing the circuit, thus vitalizing the electromagnet, which will attract its armature against the resiliency of the spring X, and as the magnet is revolving with the shaft P the disk will be caused to revolve also, thereby lifting 15 the hammer. As the spindle continues to revolve, the eccentricities in the needle or wire will be carried beyond the contact-lever A' and the circuit thereby broken, thus causing the magnet to lose its vitality and consequently its hold on the disk, which will allow 20 the hammer to fall on the said needle. The hammer may be assisted in its fall by a coil-spring, H', attached to its handle and the bed-plate. As the needle is fed in front of the 25 contact-lever throughout its entire length, it will be made perfectly true. To return this spindle to its starting-point, it is only necessary to disengage the sectional nut from the thread on said spindle, when the latter can be 30 readily thrown back.

It is obvious that the above-described machine may be varied considerably without departing from the spirit of my invention, and I do not wish to be limited by the same, and I 35 have shown in Fig. 4 one of the many modifications which may be used. In this modification the spindle and its bearings remain, but instead of the gearing, magnet, disk, &c., a solenoid, A'', is supported above the anvil, 40 and its loose armature B'' forms the handle of

the hammer C''. Now, when the circuit is completed, as before described, the hammer is raised by the magnetic influence of the solenoid, and when the circuit is broken it is allowed to fall.

50

In the drawings I have represented the circuit as passing through the needle or object to be straightened; but this is not essential, as the lower end of the contact-lever may form the circuit-closer, and the circuit be carried from thence directly to the negative binding-post G'. Neither is it absolutely necessary that the closing of the circuit raises the hammer, as it may be the means of tripping or lowering the same, as will be readily understood.

55

6c

The gist of my invention rests in the broad idea of revolving the object to be straightened across the path of the straightening mechanism and controlling the operation of the straightening mechanism by the direct action of the eccentricities of the object to be straightened.

65

Having thus described my invention, what I claim as new, and desire to secure by Letters Patent, is—

70

1. The method herein described of straightening needles, wire, &c., the same consisting in revolving the object to be straightened and passing it across the path of the straightening device, and causing the eccentricities of said object to operate the straightening device.

75

2. The method herein described of straightening needles, wire, &c., consisting in revolving the object to be straightened and passing it across the path of an electrically-controlled straightening device, and causing the eccentricities of said object to operate the electrical controlling mechanism.

80

In testimony whereof I affix my signature in presence of two witnesses.

GEORGE M. EAMES.
